US00D879988S

(12) **United States Design Patent** (10) **Patent No.:** **US D879,988 S**
(45) **Date of Patent:** **** Mar. 31, 2020**

(54) **MALE MASTURBATION TOOL**

(71) Applicant: **SHENZHEN ZHUOLE E-COMMERCE CO., LTD**, Shenzhen (CN)

(72) Inventor: **Dan Zhou**, Shenzhen (CN)

(73) Assignee: **SHENZHEN ZHUOLE E-COMMERCE CO., LTD**, Shenzhen (CN)

(**) Term: **15 Years**

(21) Appl. No.: **29/700,912**

(22) Filed: **Aug. 6, 2019**

(51) LOC (12) Cl. **28-03**

(52) U.S. Cl.

USPC **D24/215**

(58) **Field of Classification Search**

USPC ..... 601/15, 18, 19, 46, 47, 48, 52, 99, 112, 601/113, 118, 125, 129, 134, 135, 137, 601/DIG. 12, DIG. 14, DIG. 15, DIG. 16, 601/DIG. 17; D24/133, 200, 211, 212, D24/213, 214, 215; 600/38, 39, 40, 41; 604/317; 128/844

(57) **CLAIM**

The ornamental design for a male masturbation tool, as shown and described.

DESCRIPTION

FIG. 1 is a perspective view of a male masturbation tool showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the male masturbation tool that form no part of the claimed design.

1 Claim, 8 Drawing Sheets
